TELEPHONE-EXCHANGE SYSTEM.

SPECIFICATION forming part of Letters Patent No. 760,573, dated May 24, 1904.

Application filed September 15, 1902; Serial No. 123,402. (No model.)

To all whom it may concern:

Be it known that I, CHARLES E. SCRIBNER, a citizen of the United States, residing at Jericho, in the county of Chittenden and State of Vermont, have invented a certain new and useful Improvement in Telephone-Exchange Systems, of which the following is a full, clear, concise, and exact description.

My invention relates to a telephone-exchange system, and more particularly to a system of the type wherein current for the telephonic transmission and signaling apparatus is supplied from a centralized source of current located at the central office. In systems of this type heretofore in general use it has been customary to provide circuits which require the extension of two conductors through the multiple switchboard for conveying the telephonic currents and one conductor in addition thereto in connection with the local signaling-circuits. The use of three conductors in the circuit involves the necessity of employing plugs, jacks, and associated apparatus having a like number of parts. Where conditions are such as not to require the termination of a great number of telephone-lines in a limited space, the employment of such systems is permissible; but where considerations of economy and efficient operation require that a great many lines be provided with terminals within the reach of a single operator it is desirable to reduce the conductors in the switchboard for each line to the smallest number possible consistent with the proper operation of the automatic supervisory signals and efficient transmission of voice-currents.

The object of my invention is, in general, to provide a system which will be marked by greater simplicity in the arrangement and character of the switching apparatus at the central office.

More particularly, my object is to provide a system of circuits for use in multiple switchboards wherein, although two conductors may be used for each telephone-line between the substation and the central office, automatic operation of the supervisory signals, together with efficient transmission of telephonic and

ringing current, may be secured by the extension through the multiple switchboard of but one conductor for each line instead of the two or more conductors usually employed.

To this end an important feature of my invention consists in conductively dividing a telephone-line by means of an induction device including in that portion which extends to the substation a source of current and a magnetic switch controlled by the switch-hook at the substation and including directly in the connecting cord-circuit by means of which one telephone-line is united to another a signal, with means for operating it controlled by the magnetic switch when connection is made with the line.

Another feature of my invention consists in so constructing the induction device and associating it with the circuit that it operates to display the line-signal when the circuit of the line is closed at the substation and to efface it when connection is made with the line.

Other features of my invention will appear hereinafter.

I will describe my invention more particularly with reference to the accompanying drawing, which illustrates by means of conventional symbols two telephone-lines extending from their respective substations to a central office and there provided with a connecting cord-circuit for uniting them, the whole being equipped and arranged in accordance with my invention.

Each telephone-line comprises two conductors 1, 2, which extend from the usual telephonic apparatus at the substations A, B to the central office C. In the circuit of the line conductors at the central office are included the winding of a line-relay a , shunted by a non-inductive resistance a' ; a central battery b , one pole of which may be grounded; a resistance c , and one winding, d' , of a repeating-coil d . Inasmuch as this repeating-coil is provided with an armature and acts both as a repeating-coil and a relay, I will refer to it hereinafter as a "repeating-coil" relay. The repeating-coil relay d contains two other windings, d^2 and d^3 , which are included serially in

a conductor 3, which extends from the contacts of jacks $e'e'$ to earth or a return-conductor. One of these windings d^2 is short-circuited in normally closed contacts of relay a . The repeating-coil relay d is so arranged that a certain magnetizing force will cause the armature to be attracted to close a contact, while any magnetizing force in excess of this predetermined amount will cause the armature 10 to be attracted further to break one contact and close another. Relays adapted to act in this manner are old in the art and of widely-varying structure. In the form which I have illustrated a lever d^4 normally rests against the 15 contact-point d^5 . The armature d^6 when attracted is adapted to make contact with lever d^4 and move it away from contact-point d^5 and against contact-point d^7 . The normal pressure of lever d^4 against contact-point d^5 20 may be so regulated by means of a light helical spring d^8 that any attractive force less than a predetermined amount will merely serve to move armature d^6 into contact with lever d^4 without breaking the contact between 25 the lever d^4 and contact-point d^5 , while if the attractive force is in excess of this predetermined amount the retractile force of spring d^8 will be overbalanced and contact will be made through the medium of lever d^4 between armature d^6 and contact-point d^7 . A 30 signal-lamp f is associated with the answering-jack e' of the line and is included in the circuit 4, which extends from the free pole of the central battery b to contact d^6 of the 35 repeating-coil relay. The armature of this relay is connected to earth. The contact-point d^7 is connected with line conductor 2 at a point between the resistance c and the winding d^9 of the repeating-coil relay. 40 It follows from this arrangement that when armature d^6 is drawn up far enough to make contact with lever d^4 without causing said lever to move away from contact-point d^5 the circuit 4 is completed and the signal-lamp f is 45 illuminated. When the attractive force is such that the armature is drawn up to its full extent, the connection between armature d^6 and contact-point d^7 through the medium of lever d^4 is broken, while the connection between armature d^6 and contact d^7 through the 50 medium of the lever is completed. This action opens circuit 4, thereby causing the lamp f to be extinguished, and completes a short circuit of resistance c . The resistance c is included in the circuit of the line in order to prevent the current-flow through the line-circuit, should the resistance of the line happen 55 to be low, from rising when the telephone is taken off the hook to that value where the 60 magnetizing force generated in repeating-coil relay d would be sufficient to move its armature d^6 to interrupt the circuit of line-signal f instead of closing it. When connection is completed with the line, the resistance is no 65 longer required and is therefore short-cir-

cuted in order that it may not impede the flow of transmission-current.

The connecting cord-circuit comprises plugs $g\ g'$, united by a conductor 5, which includes serially the two supervisory signal-lamps $h\ h'$ 70 and the two windings of a repeating-coil i . The battery b is connected in a bridge to ground from a point in the cord-circuit intermediate of the two windings of the repeating-coil i . The operator's telephone apparatus 75 and a source of ringing-current l are associated with the connecting cord-circuit and controlled by keys in the usual manner. The calling-plug g' of the pair is furnished with an auxiliary contact-piece or test-tip g^2 , which 80 may be permanently connected, through a third winding of the operator's induction-coil, to ground. This test-tip is adapted to project beyond and be insulated from the line-spring of the jack into which it may be inserted 85 and its only function being to indicate the presence of a test potential on the jack of a busy line into which it may be inserted. The windings of the repeating-coil i and the supervisory signal-lamps $h\ h'$ are preferably of 90 low resistance, each winding having a resistance of, say, forty ohms and each lamp a resistance of, say, twenty ohms and requiring a current of approximately two-tenths ampere for its illumination. The resistance of 95 winding d^9 of the repeating-coil relay d may be two hundred and fifty ohms. The resistance of winding d^2 may be one hundred and seventy ohms, and the resistance of winding d^3 may be eighty ohms. The resistance of resistance-coil c may be five hundred ohms and the electromotive force of the central battery b twenty-four volts. 100

Although three batteries have been shown for the sake of clearness in the drawing, it 105 will be understood that in accordance with the usual practice these may be one and the same battery.

The operation of the system is as follows: 110 The subscriber at substation A desiring connection with another subscriber—say the subscriber at substation B—takes his telephone from the hook and in so doing allows the telephone-switch to close its contacts and complete the circuit of the telephone-line. The 115 current flowing from battery b in the circuit thus completed energizes the magnets of relay a and repeating-coil relay d and causes them to attract their armatures. The armature of relay a in drawing up breaks the normal short circuit of winding d^2 of repeating-coil relay d . The magnetizing force generated under these conditions in the repeating-coil 120 relay d is only sufficient to cause armature d^6 to be attracted into contact with lever d^4 without forcing lever d^4 away from the contact-point d^5 . The circuit of conductor 4 is thus completed and line signal-lamp f is illuminated. The operator upon seeing the illumination of lamp f inserts the answering-plug 125 130

g of a pair of connecting-cords into the answering-jack e', associated with the lighted lamp. Current then flows from battery b through circuit 5 3, completed in registering-contacts of the answering plug and jack, this circuit including one winding of repeating-coil i, supervisory lamp h, and windings d² and d³ of the repeating-coil relay. The short circuit of winding d² of the repeating-coil relay being broken in contacts of relay a, current flows through windings d² and d³, and the attractive force generated thereby in addition to that generated in winding d¹ is sufficient to cause armature d⁶ to sever connection with contact-point d⁵ and close connection with contact-point d⁷, thus extinguishing the line signal-lamp f and short-circuiting resistance-coil c. The short circuit placed around resistance-coil c increases the flow of current in the line-circuit and through winding d', and thus strengthens the attractive force upon the armature. The current which flows through the circuit composed of conductors 5 3 and the included apparatus is sufficient to illuminate supervisory lamp h, which consequently remains dark. As the windings d² d³ of the repeating-coil relay are in inductive relation with the winding d', which is included in the circuit of the telephone-line 1 2, extending to the calling-substation, the operator by operating the key which connects her telephone-circuit with the line may place herself in communication with the calling-subscriber and inquire the number of the line with which he desires connection. Upon learning this she tests by touching the test-tip g² of the calling-plug of the pair of cords to the multiple jack e of the line called for and finding that the line is not in use inserts the plug and by depressing key k causes ringing-current from the grounded source l to flow through winding d³ of repeating-coil relay d. This induces a current in winding d', which being included in the line-circuit effects the operation of the bell at station B. When the calling-plug is first inserted in the jack of the called line, current flows to earth from battery b, through supervisory lamp h', by way of conductors 5 3 and winding d² of the repeating-coil relay associated with the called line. Until the called subscriber responds to the call winding d² of the repeating-coil relay of his line is short-circuited in the normally closed contacts of the relay a of the called line. The resistance of winding d² is made low, as hereinbefore described, so that under these conditions the flow of current through the circuit 5 3 is sufficient to cause the illumination of supervisory lamp h'. The comparatively heavy current which flows in the circuit of conductors 5 3, owing to winding d² of the repeating-coil relay associated with the called line being short-circuited, is sufficient to generate an attractive force in the repeating-coil relay which draws

the armature up as far as it will go, thus breaking the circuit of the line signal-lamp f of the called line and completing the short-circuit of resistance c as soon as the calling-plug is inserted. When the subscriber, responding to the ringing of his bell, removes his telephone from the hook, circuit is immediately completed for current to flow from battery b over the line conductors 1 2 through the included apparatus at the substation in the central office. This current flowing through relay a causes it to operate to break the short circuit of winding d² of the repeating-coil relay. The additional resistance which is thus thrown into the circuit of conductors 5 3 is sufficient to so reduce the current flowing therein that the supervisory lamp h' is extinguished. The current which, as soon as the called subscriber removes his telephone from the hook, circulates in winding d' of the repeating-coil relay is such as to augment the effect of that which has been circulating in winding d³ and which upon the actuation of relay a flows serially through windings d³ and d², so that the armature d⁶ is held in the same position to which it was moved by the current primarily flowing in winding d³. When the subscribers have finished their conversation, the replacing of their telephones upon the hooks breaks the circuit of the lines and causes the deenergization of line-relays a a. The armatures of these relays falling back reestablish the normal short circuits of windings d² d³ of the repeating-coil relays associated with their line-circuits. The resistance in circuits 5 3 5 3 being thus reduced, current sufficiently great to effect the illumination of supervisory lamps h h' and the continued full energization of repeating-coil relays d d is caused to flow. The illumination of both supervisory signal-lamps is taken by the operator as a signal for disconnection.

Having thus described my invention, I claim as new, and desire to secure by Letters Patent, the following:

1. The combination with a telephone-line extending from a substation to a central office, of a switch at the substation controlling the circuit of the line, a source of current, a relay, and a winding of a repeating-coil included in the circuit of the line at the central office, a local telephone-circuit, a second winding of the repeating-coil, a source of current, and a signal device included therein, and means controlled by the aforesaid relay adapted to vary the resistance of the local circuit to effect the actuation of the signal device, substantially as described.

2. The combination with a telephone-line extending from a substation to a central office, of a line-relay, one winding of a repeating-coil, and a source of current included in the circuit of the line at the central office, a switch for controlling the circuit of the line at the substation, a connection-terminal for the line,

and means for making connection with the line at said connection-terminal, a second winding for said repeating-coil and a local circuit therefor completed at said connection-terminal in making connection with the line, a signal device, a source of current included in said local circuit, and circuit connections controlled in contacts of the line-relay adapted to alter the resistance of the local circuit upon the 10 operation of said relay, whereby the signal device is actuated.

3. The combination with a telephone-line extending from a substation to a central office, of a switch at the substation for controlling the flow of current in the line, a source of current, and a relay in the circuit of the line at the central office, said relay being also adapted to act as a repeating-coil, a line-signal displayed through the agency of said relay, a 15 spring-jack for the line, a plug and plug-circuit for making connection therewith, a second winding of the aforesaid relay in inductive relation with the first-mentioned winding, and a local circuit therefor completed in 20 making connection with the line, a signal device and a source of current in said local circuit, the flow of current in said local circuit operating to actuate the signal device and to 25 operate the aforesaid relay to efface the line- 30 signal, and a second relay in the circuit of the line controlled by the telephone-switch at the substation operating to alter the resistance of the local circuit to effect the deenergization of the aforesaid signal device, substantially 35 as described.

4. The combination with two telephone-lines, each extending from a substation to a central office, of a source of current, a line-relay, and one winding of a repeating-coil in 40 the circuit of each line at the central office, a switch at each substation for controlling the flow of current in the line, a second winding for each repeating-coil, a spring-jack for each line connected with one terminal of said 45 second winding, the other terminal being connected to earth, a pair of plugs and a single conductor plug-circuit for uniting the lines at the spring-jacks thereof, an inductive device conductively dividing the plug-circuit, a 50 grounded source of current connected with the plug-circuit through the induction device, supervisory signals included in the plug-circuit, one between each plug and the induction device, and circuit connections of the second 55 winding of each repeating-coil controlled in contacts of the line-relay of that line, whereby the supervisory signals of the plug-circuit are controlled from the substations of the lines with which they are connected.

6. The combination with two telephone-lines extending from their substations to a central office, each line having two limbs united at the central office through a winding of a repeating-coil and a source of current, of 65 a switch at the substation of each line for de-

termining the flow of current therein, a spring-jack for each line and a pair of plugs and their plug-circuit for uniting the lines at the spring-jacks thereof, a second winding for each repeating-coil, one terminal of said winding being connected to earth and the other terminal to the spring-jack of the line, two signals included in the plug-circuit, a grounded source of current connected with the plug-circuit at a point between the two signals, 70 and a relay in the circuit of each line adapted to vary the resistance of the circuit including the second winding of the repeating-coil, whereby the signals in the plug-circuit are 75 controlled.

6. The combination with two telephone-lines extending from substations to a central office, and a link conductor temporarily uniting the same for conversation, of a repeating-coil interposed in the circuit of one of the lines, said repeating-coil having three windings, one of said windings being included with a source of current in the circuit of that portion of the line extending to the substation, the other two windings being included serially in the circuit of that portion of the line united to the other telephone-line through the link conductor, a signal and a source of current also included in the circuit with the two last-mentioned windings of the repeating-coil, said signal being adapted to operate upon an increase of current, a short circuit of one of the two last-mentioned windings of the repeating-coil, an electromagnetic switch for controlling the same included in 90 the portion of the line extending to the substation, and a switch at the substation controlling the circuit of the line, whereby the signal is actuated.

7. The combination with two telephone-lines 105 extending from substations to a central office, and a link conductor temporarily uniting the same for conversation, of a repeating-coil interposed in the circuit of one of the lines, said repeating-coil having three windings, one of said windings being included with a source of current in the circuit of that portion of the line extending to the substation, the other two windings being included serially in the circuit of that portion of the line united to the other telephone-line through the link conductor, a signal and a source of current also included in the circuit with the two last-mentioned windings of the repeating-coil, said signal being adapted to operate upon an increase of current, a short circuit of one of the two last-mentioned windings of the repeating-coil, an electromagnetic switch for controlling the same included in the portion of the line extending to the substation, a switch at the substation controlling the circuit of the line, an armature for the repeating-coil, and a line-signal controlled thereby, substantially as described.

8. The combination with a telephone-line 130

extending from a substation to a central office, and a switch for controlling the circuit of the same, of a source of current and a winding of a repeating-coil included in the circuit of the line at the central office, a local telephone-circuit including another winding of the repeating-coil and a source of current, a switch for completing said local circuit in making connection with the line, an armature for the repeating-coil, and a signal controlled thereby, said armature being adapted to display the signal in response to current in one winding of said repeating-coil, and to conceal the signal in response to current in both windings of said repeating-coil, substantially as described.

9. The combination with two telephone-circuits, of a repeating-coil having a winding in each circuit, a source of current and a switch

in each circuit for controlling the flow of current therein, an armature for the repeating-coil and contacts controlled thereby, and a signal having a circuit controlled in said contacts, the windings of the repeating-coil being so proportioned that the attractive force produced by current flowing in one of the windings alone moves the armature part way to close said signal-circuit, while current flowing in the other winding or in both windings at once attracts the armature further to open the signal-circuit.

In witness whereof I hereunto subscribe my name this 23d day of July, A. D. 1902.
